UNITED STATES PATENT OFFICE.

HARRY TASAKA, OF CHICAGO, ILLINOIS.

SLICING MACHINE.

Application filed November 8, 1920. Serial No. 422,472.

To all whom it may concern:

Be it known that I, HARRY TASAKA, a subject of the Emperor of Japan, and a resident of Chicago, in the county of Cook and State of Illinois, have invented certain new and useful Improvements in Slicing Machines, of which the following is a full, clear, and exact description.

The invention relates to slicing machines and its object is to provide a machine which is simple in construction and efficient in operation.

The invention consists in the several novel features and combinations hereinafter set forth and more particularly defined by claims at the conclusion hereof.

In the drawings: Fig. 1 is a side elevation of a machine embodying the invention. Fig. 2 is a plan. Fig. 3 is a section taken 20 on line 3—3 of Fig. 2. Fig. 4 is a perspective upon an enlarged scale of a portion of the feed mechanism.

The improved machine comprises a box or holder composed of a bottom 6, a front 7, and a back 8 adapted to hold the product, such as a loaf of bread, which is to be sliced. This box or holder is extended beyond the point at which the slicing knife operates so as to retain the slices until an 25 entire load has been sliced, so that all of the slices from a loaf may be removed together and wrapped before being separated, if desired. This box is sustained by suitable legs or standards 9. The box is formed with 30 a gap 10 through which a scimitar-shaped knife 11 on a shaft 12 is adapted to rotate in slicing the bread. A plate 13 is extended across the back of the gap to secure the box-portions in connected relation. The 35 knife 11 is scimitar-shaped to effect a shear cut during each revolution of the shaft 12. Said shaft is journalled in bearings 14 formed on standards 9. The hub of the knife 11 is secured to one end of the shaft 40 12 and a wheel 15 with a handle 16 forming a crank is secured to the other end of the shaft so that it may be manually rotated to operate the knife.

The automatic feed mechanism for feeding the loaf between the slicing operations comprises a pusher 17 adapted to move longitudinally back and forth in the box. This pusher is provided with an integral arm or extension 18 outside of the box 45 which is provided with a hub 19 through which the shaft 12 passes. This hub is

slidable on the shaft 12. The mechanism for operating the pusher 17 step by step comprises a cam 20 on the wheel 15, a bar 21 which is slidably mounted in bearings 60 22 integral with two of the standards 9 and provided with ratchet-teeth 23 to engage a pawl 24 which is pivoted, as at 25, to the arm 18 on the pusher, a member 26 secured to one end of the ratchet-bar 21 provided 65 with a roller 27 adapted to be engaged by the cam 20 to operate the ratchet-bar in one direction and a spring 28 applied to said member to retract the ratchet-bar. Spring 28 is coiled around a post 29 which is fixed 70 to, and projects from, one of the standards 9 and is provided with a nut 30 by which the retractile stroke of the bar 21 may be varied to regulate the length of the steps which the pusher will be advanced during 75 the revolutions of the cam 20. By adjusting the nut 30 to restrict or extend the retractile stroke of the bar 21, the distance advanced by the pusher will be varied so that the thickness of the slices cut from the loaf 80 85 may be varied as desired. A dog 31 is pivoted to ears 32 formed on the arm 18 and engages a rack or series of teeth 33 formed on the front side 7 of the box to prevent retraction of the pusher with the 85 bar 21. This dog is provided with a handle 34 and pawl 24 is provided with a handle 35 by which they may be disengaged from the ratchet-teeth 33 and the ratchet-bar 21 respectively, so that the pusher may be 90 95 manually retracted to receive a loaf to be sliced.

In operation, the loaf to be sliced is placed in the box while the pusher 17 is retracted. To slice the bread, it is then only 95 necessary to rotate the handle 16 which will operate the knife 11 to cut one slice from the loaf during each rotation of shaft 12. Between the cutting and slicing operations, the cam 20 will engage roller 27 to move 100 the ratchet-bar 20 to the left which will, through pawl 24 and arm 18, advance the pusher one step. The spring 28 will retract the ratchet bar 21, arm 26 and roller 27 between the advancing strokes of the 105 pusher and the latter will be held against retraction by the dog 31 and teeth 33. By adjusting the wing nut 30, the stroke of the pusher may be regulated according to the thickness of the slice desired. The 110 slices severed from the loaf pass into the left-hand portion of the box in the order

in which they are severed from the loaf, so that the slices may be kept together in the order in which they are cut from the loaf.

5 The invention exemplifies a slicing machine which is simple in construction and efficient in operation.

The invention is not to be understood as restricted to the details set forth, since 10 these may be modified within the scope of the appended claims, without departing from the spirit and scope of the invention.

Having thus described the invention, what I claim as new and desire to secure by Letters Patent, is:

1. In a slicing machine, the combination of a holder comprising a bottom and sides and having an open top; a shaft extending longitudinally of the holder, disposed outwardly of one of the holder sides and mounted in stationary bearings, a knife secured to said shaft and adapted in its rotation to cut a slice from a loaf in the holder, a pusher operating in said holder extended over one of the sides and provided with a bearing outwardly of the latter side extending around said shaft to guide the holder, means for rotating said shaft, and means for operating the pusher step by step.

30 2. In a slicing machine, the combination of a holder comprising a bottom and sides and having an open top, a shaft extending longitudinally of the holder disposed outwardly of one of the holder sides and mounted in stationary bearings, a knife secured to said shaft and adapted in its rotation to cut a slice from a loaf in the holder, a pusher operating in said holder and extended over one of the sides, means for rotating the shaft, mechanism for operating the pusher step-by-step comprising a reciprocable bar disposed outwardly of one side of the holder, and means on the pusher for guiding it extending around said shaft and said bar.

3. In a slicing machine, the combination of a holder comprising a bottom and sides and having an open top; a shaft extending longitudinally of the holder, disposed outwardly of one of the holder sides and mounted in stationary bearings, a knife secured to said shaft and adapted in its rotation to cut a slice from a loaf in the holder, a pusher operating in said holder and ex-

tending over one of the holder sides, means for rotating the shaft, a cam on said shaft, and means for operating the pusher step by step from said cam comprising a reciprocable toothed bar disposed outwardly of one of the holder sides and provided with means directly thereon engaged by said cam to reciprocate the bar.

4. In a slicing machine, the combination of a holder comprising a bottom and sides and having an open top; a shaft extending longitudinally of the holder, disposed outwardly of one of the holder sides and mounted in stationary bearings, a knife secured to said shaft and adapted in its rotation to cut a slice from a loaf in the holder, a pusher operating in said holder and extending over one of the holder sides, means for rotating the shaft, a reciprocable toothed bar, disposed outwardly of one of the holder sides, means for reciprocating said bar from the shaft, a stationary toothed bar and a plurality of pawls mounted on and movable with the pusher and adapted to engage said bars respectively.

5. In a slicing machine, the combination of a holder comprising a bottom and sides and having an open top; a shaft extending longitudinally of the holder, disposed outwardly of one of the holder sides and mounted in stationary bearings, a knife secured to said shaft and adapted in its rotation to cut a slice from a loaf in the holder, a pusher operating in said holder and extending over one of the holder sides, means for rotating the shaft, a reciprocable toothed bar disposed outwardly of one of the holder sides, a pawl on the pusher adapted to be operated in one direction by said bar, a fixed toothed bar and a pawl on the pusher adapted to engage the fixed bar to prevent retraction of the pusher.

6. In a slicing machine, the combination of a holder, a shaft mounted in stationary bearings, a knife secured to said shaft and adapted in its rotation to cut a slice from a loaf in the holder, a pusher operating in said holder, means for rotating the shaft, a reciprocable toothed bar, the holder being provided with a side, a fixed toothed bar on the top of said side, and a plurality of pawls on the pusher and engaging said toothed bars respectively.

HARRY TASAKA.
